UNITED STATES PATENT OFFICE.

VAL F. FRANCK, OF LOUISVILLE, KENTUCKY, ASSIGNOR OF ONE-HALF TO E. H. HINKEBEIN, OF LOUISVILLE, KENTUCKY.

RAILROAD-TIE.

1,400,737.

Specification of Letters Patent. Patented Dec. 20, 1921.

Application filed May 20, 1920. Serial No. 332,761.

To all whom it may concern:

Be it known that I, VAL F. FRANCK, a citizen of the United States, residing at Louisville, in the county of Jefferson and 5 State of Kentucky, have invented certain new and useful Improvements in Railroad-Ties, of which the following is a specification.

This invention relates to railroad ties and 10 more particularly to metallic ties of hollow construction wherein suitable filler means may be deposited and contained for giving the desired resiliency to the tie.

The principal object of the invention is to 15 provide an improved tie of the character above referred to, which comprises separable and independent sections adapted to be associated with each other in locked relation yet resiliently movable under the 20 stress of the passing rolling stock.

A further object of the invention is to provide an improved form of metallic tie in which the sections are provided with means for facilitating relative sliding engagement; one section being further provided with an extended, reinforced, base; while the coöperating section carries improved rail fastening means.

With the above and other objects in view, 30 the invention resides generally in the combination and arrangement of parts, as are hereinafter more fully pointed out and explained, reference being had to the accompanying drawings wherein—

35 Figure 1 is a fragmentary, perspective view of one end of a tie constructed in accordance with the invention.

Fig. 2 is a vertical, cross sectional view of the tie illustrating the position of the 40 joints when the tie is filled with wood fiber.

Fig. 3 is a similar section disclosing the position of the joints when the tie is carrying a load.

Fig. 4 is a view in detail of one of the 45 rail locking wedges, and

Fig. 5 is a vertical, sectional view across the corner of a tie section disclosing the manner of connecting the sides and ends thereof.

50 This improved device consists of a hollow casing, of pressed steel, or other suitable and durable material, preferably filled with wood fiber, although any other filler, including rubber scraps, etc., may be used and 55 this casing is formed of an upper and a

lower box-like section, which fit together, one within the other.

The lower section has the base 1 lapped over at its sides to provide extensions 2 which thus being of a double ply of mate- 60 rial, add strength to and reinforce the bottom of the tie. The side walls 3 extend upwardly from the inner, spaced edges of

the extensions and have their upper marginal portions bent outwardly and down- 65 wardly to provide hooked-flanges 4 overhanging the base extensions and spaced an appreciable distance thereabove. Each side wall 3 is, moreover, provided with inwardly directed, vertical, end flaps 5 welded or 70 otherwise fastened to the end walls 6 of the lower section, upon the inside of the latter; it being noted that each end wall has its upper end 7 bent downwardly and over the upper ends of the flaps to which 75

they are fastened. As thus made up, the lower section is designed to receive the top section which fits over it after the manner of a cover; the two sections being joined together in a manner to be hereinafter ex- 80 plained. The upper section is practically an equivalent of the lower section; the particulars in which they differ being apparent from the drawings and the following disclosure. Each side wall 8 of the upper sec- 85

tion is similarly provided with vertical end flaps, after the manner of the lower section, and these flaps 9 fold over the end walls 10 interiorly of the box so as to be welded or otherwise made permanent to such end 90 walls; it being here understood, however, that only one end of the top section is to be so closed, the other remaining open until the sections have been connected together to form the tie casing and the filler material 95 properly packed therein.

Hook-flanges 11 extend longitudinally of the side walls 8, being similar to the hook flanges carried by the lower section, except that in this instance the flanges extend in- 100 wardly of the section with their terminal ends in spaced relation to the top wall 12. In assembling the sections, the top one is slipped over the lower one so that the flanges 11 will pass under and rearwardly of the 105 flanges 4; each flange thus hooking over the other and interlocking to provide a joint for retaining the sections together. The wood fiber or other filler material may then be packed in the casing through the open end 110

of the upper section until the tie is completely and compactly filled; the maximum capacity being attained when the sections are relatively so expanded that their respective flanges are fully interlocked, as shown to advantage in Fig. 2. Both sections are further fastened against displacement upon the sealing of the open end of the upper box, which sealing completes the tie; it being evident that the two sections cannot be separated as long as the sides and ends of the upper section fit over and around the lower section; the end walls of each section acting as abutments to prevent any relative, 15 longitudinal, sliding movement.

Arranged adjacent the opposite ends of the upper surface of the tie thus formed are a pair of rail braces 13 which extend transversely of the top wall 12 from one side to 20 the other so as to accommodate therebetween the track rails to be supported upon the tie; a sufficient space being provided between the braces of each pair to permit the base flange of the rail to pass easily and squarely there- 25 between without it being necessary to turn the rail to either side in order to slip it into place. These braces are preferably to be pressed in the casing, being made an integral part of the upper wall 12 and are 30 each provided with a vertical wall 14 disposed in laterally spaced, parallel relation to the rail, with its inner face 15 disposed angularly with respect to the adjacent edge of the base flange of the rail so as to provide 35 a tapering passage or key way 16, between the wall of the brace and such edge of the rail flange, into which key-way is adapted to be received the tapering wedge of the rail locking key. These tapering passages are 40 arranged with their wide ends opening on opposite sides of the tie and the overhanging portion 17 of the brace is designed to extend over above the passage so provided and fit partially over upon the locking key. 45 This locking key comprises a rail clamp 18 and a tapering wedge 19 formed from a single strip of heavy material such as malleable iron or steel, and arranged so that the rail clamp member lies in a plane above the 50 wedge member, thus providing a shoulder portion 20 between the members, which is adapted to abut, on one side, against the edge of the rail flange as indicated at 21, and on the opposite side, against the edge of the 55 brace as indicated at 22. The wedge member of the key is designed to take up space and to bring the clamp into binding position against the flange of the rail, making an absolutely tight joint and preventing looseness of, or creeping of the rail and is rather long and tapering projecting beyond the clamp on one side to provide a nose portion 23 which may be bent downwardly to lock the key in place.

60 In operation, the flanges of the rails to

be supported are placed between their respective pair of braces 13 so as to rest upon the top wall 12 of the tie, the latter resting solidly upon its enlarged base 1, the reinforced sides 2 of 70 which would ordinarily be embedded beneath the cinders or other material usually packed around each tie throughout the stretch of track. To firmly lock the rail to the tie, a locking key is arranged on each 75 side of the base flange, being inserted between the rail and the braces 13 and from opposite sides of the tie, so that the wedge enters the key-way 16 while the clamp engages over the base flange. Each key is inserted under a brace 13 at the widest end of the tapered key way 16, the head entering the latter with its nose 23 preceding so that as the key is driven or otherwise forced in between the rail and the brace, the angularly disposed wall 15 of the latter urges the key over against the rail and since there is a key on each side of the rail, working opposite to each other, it is obvious that the rail will be firmly clamped between the 80 two keys, which will of course become wedged in place as the wedge portions 19 are forced more and more toward the restricted end of the tapered keyway. Each 85 brace, it may be here observed, extends over upon the wedge of the key so as to be practically flush with the upper surface of the clamp portion thereof, thus insuring a smooth surface, the inner terminal edges of the braces abutting the shoulders 20 and 90 tending to guide the keys while they are being driven in place. To more positively hold each key in place, the nose 23 is bent downwardly over the edge of the tie and against the side wall as shown to advantage 95 in Fig. 1 of the drawings, in which position it prevents the key from being withdrawn through or working back out of the wide end of the key way. As the filler material contained within the sectional tie-casing would 100 ordinarily be of wood fiber or like substance, and resilient in character, it is obvious that a slight vertical play of the two sections is permitted by reason of the space between the terminal edges, during the passage of 105 rolling stock thereover, permitting the upper section to be depressed slightly under the stress of a heavy load, the degree of depression being in accordance with the character of the load and in the event of the upper 110 section being depressed to its maximum extent, it is to be particularly noted that the side walls of the top section rest upon the reinforced sides of the base, while the side walls of the lower section extend upwardly 115 to support and reinforce the top wall 12 of the upper section; the hooked flanges of both sections still overlapping one another, as indicated at 24 in Fig. 3, so as to enable 120 them to easily and readily interlock as the 125 130

top section moves upwardly when released or freed from the load.

It may thus be seen from the foregoing that the invention provides not only a solid undersupporting tie structure for the rail but one which is at the same time yieldable so as to better withstand the strain to which the devices of this nature are ordinarily subjected; the filler means within the box-like sections providing the necessary resilient packing for solidifying the metallic structure, as previously pointed out.

As will be evident from the drawings, the upper section of the tie is slid horizontally and endwise upon the lower section of the tie after which time the corners 9 are bent to closed position.

Although the foregoing may be considered as having reference to what may be termed the preferred embodiment of the invention, it is to be understood that such changes in regard to proportion of parts, arrangement and details thereof may be resorted to as properly fall within the scope of the invention claimed, and which are consistent with the purposes and objects of the device as hereinbefore stated.

Having thus described the invention what I claim as new and desire to secure by Letters Patent is:

1. A railroad tie comprising a casing formed of upper and lower box-like sections designed to fit, one within the other, filler means inclosed within the said sections, rail holding means on the upper section, and flanges on both sections arranged for mutual interlocking engagement to hold the sections together.

2. A railroad tie comprising a casing formed of top and bottom box-like sections designed to fit one within the other, filler means within the casing, rail holding means

on the top section and flanges on the opposed sides of the two sections and adapted for mutual interlocking engagement to permit upward movement of the upper section.

3. A railroad tie comprising a sectional casing formed of a lower box-like, base section and an upper box-like rail supporting section fitting over the base section, filler means between the sections and means arranged inwardly of the opposed side walls of the said upper box-like section for mutual interlocking engagement whereby vertical adjustment of the connecting sections may be permitted.

4. A railroad tie having an enlarged base having side portions folded inwardly to provide reinforced side extensions, and having portions extending upwardly in spaced relation from the sides of the base to provide a box-like receptacle, portions bent outwardly and downwardly along the upper side edges of the receptacle and terminating above the base thereof, an upper section comprising a box-like structure adapted to be fitted over the box-like receptacle of the lower section and having flanges bent inwardly in spaced relation to its side walls, the inner flanges of the said upper section adapted to hook under the flanges of the bottom section whereby the said sections may be held against separation by the interlocking engagement of the respective hooked flanges, filler means contained within said connected sections and adapted to provide a resilient filler therefor, and rail holding means provided on said upper section.

In testimony whereof I affix my signature in presence of two witnesses.
